(57) **CLAIM**

The ornamental design for an air conditioner indoor ceiling unit as shown and described.

DESCRIPTION

FIG. 1 is a lower back perspective an air conditioner indoor ceiling unit showing our new design;

FIG. 2 is a lower front perspective thereof;

FIG. 3 is a front view of thereof;

FIG. 4 is a left-side view thereof;

FIG. 5 is a right-side view thereof;

FIG. 6 is a back view thereof; and,

FIG. 7 is a bottom view thereof.

The top view is not shown in a drawing as it forms no part of the claimed design because it is hidden after installation.
